[57] **CLAIM**

The ornamental design for a multi-function pager charger, as shown and described.

DESCRIPTION

FIG. 1 is a front elevational view of a multi-function pager charger showing our new design;

FIG. 2 is a top plan view thereof;

FIG. 3 is a right side elevational view thereof;

FIG. 4 is a rear elevational view a thereof;

FIG. 5 is a bottom plan view thereof;

FIG. 6 is a left side elevational view thereof; and

FIG. 7 is a front and upper right perspective view thereof shown on an enlarged scale.

The broken line showing of the electrical connector is included for the purpose of illustrating environmental elements only and forms no part of the claimed design.

FIG. 1

FIG. 2

FIG. 3

*FIG. 4**FIG. 5**FIG. 6*

FIG. 7
